UNITED STATES PATENT OFFICE.

WILLIAM HENRY GREENE, OF ALEXANDER CITY, ALABAMA.

DESIGN FOR A SASH-LOCK MEMBER.

SPECIFICATION forming part of Design No. 32,994, dated July 24, 1900.

Application filed February 16, 1900. Serial No. 5,540. Term of patent 14 years.

To all whom it may concern:

Be it known that I, WILLIAM HENRY GREENE, a citizen of the United States, residing at Alexander City, in the county of Tallapoosa and State of Alabama, have invented and produced a new and original Design for a Sash-Lock Member, of which the following is a specification.

This invention relates to a new and original design for a sash-lock member; and it has for its object to provide a design of this character which shall be both useful and ornamental.

The leading feature of the design resides in the flat-sided disk of an elliptical contour with narrow rounded lobes at the ends thereof, said flat-sided disk being provided in one of its longer side portions with an angular U-shaped notch of an outwardly-flaring form and disposed at a point intermediate the end lobes, the disk being further provided with a continuously-milled peripheral edge and at both sides of its center with eccentrically-disposed openings, said openings lying in the transverse plane of the angular notch.

In the drawings, Figure 1 is a perspective view of a sash-lock member embodying the herein-described design. Fig. 2 is a plan view thereof.

Referring to the drawings, the numeral 1 designates a sash-lock member consisting of a flat-sided disk 2. This disk is of an elliptical shape with rounded narrow end lobes and is provided with a continuously-milled peripheral edge 3. One of the longer side edges of the disk-body is plain, while the diametrically-opposite side of the disk-body is provided with a reentrant approximately U-shaped angular notch 4 of an outwardly-flaring form and disposed at a point intermediate the narrow end lobes of the ellipse. To complete the design, the elliptical disk 2 is provided at both sides of its center with eccentrically-disposed openings 5, disposed in the transverse plane of the angular notch 4.

What is claimed is—

The design for a sash-lock member herein shown and described.

In testimony that I claim the foregoing as my own I have hereto affixed my signature in the presence of two witnesses.

WILLIAM HENRY GREENE.

Witnesses:

T. S. CHRISTIAN,
G. B. ARCHER.
